UNITED STATES PATENT OFFICE.

JAMES A. PALMER, OF PHILADELPHIA, PENNSYLVANIA.

STEAM-GENERATOR.

SPECIFICATION forming part of Letters Patent No. 391,639, dated October 23, 1888.

Application filed April 26, 1888. Serial No. 271,916. (No model.)

To all whom it may concern:

Be it known that I, JAMES A. PALMER, a citizen of the United States, residing in the city and county of Philadelphia, State of Pennsylvania, have invented a new and useful Improvement in Steam-Generators, which improvement is fully set forth in the following specification and accompanying drawings.

My invention consists of a steam-generator having water-legs which constitute the walls of the combustion-chamber of the furnace, the upper portion whereof serves to deflect the products of combustion to a central group of flues.

It also consists in so constructing the water-leg that the upper portion thereof directs some of the products of combustion to a peripheral row of flues.

Figure 1 represents a partial front view and partial vertical section of a steam-generator embodying my invention. Fig. 2 represents a horizontal section on line $x\alpha$, Fig. 1. Fig. 3 represents a vertical section of a detached portion thereof.

Similar letters of reference indicate corresponding parts in the several figures.

Referring to the drawings, A represents a steam-generator consisting of the vertical flues B B', through which the products of combustion pass, said flues being secured to tube-sheets C, which, with the shell D, constitute the water and steam chamber or space E.

F represents a water leg or space which communicates with the chamber E by means of tubes G, which are secured to the lower tube-sheet and the upper wall of the water-leg. The central portion of the lower tube-sheet is depressed, forming a rim which enters the upper portion of the water-leg, and the peripheral portion of said tube-sheet is above the upper wall of the water-leg, whereby the central group of flues, B, are longer than the peripheral row of flues B'. The water-leg is formed in divisions or parts trapezoidal in cross-section; but it is evident that the shape of the division may be that of a frustum of cones, so that in either case the inner wall of the water-leg is doubly inclined—that is to say, it is inclined from its base to center outwardly or diverging, and from center to top inwardly or converging. The upper end of the inner

wall of the water-leg embraces the depressed or depending rim of the bottom of the chamber E, and said wall is scalloped or corrugated, so as to permit the products of combustion to pass the top of the leg and thus reach the outer row of flues. The sections are connected by bolts H, which pass vertically through the sections and have their heads bearing against the bottom wall of the leg, and tightening-nuts against the upper wall, or vice versa.

It will be seen that the inner wall of the water-leg forms the combustion-chamber of the furnace; consequently the water in said leg will be highly heated, the water communicating with the chamber E, as has been stated. Some of the products of combustion are deflected by the converging wall or overhanging top of the water-leg to the bottom tube-sheet and the central group of flues. Another volume of the products of combustion escapes through the openings at the top of the water-leg formed by the scalloped edge thereof, and so reaches the outer row of flues and adjacent portion of the bottom tube-sheet. After the products of combustion leave the several flues they enter the shell or casing of the furnace and heat the exterior of the water-spaces, said casing having a suitable exit-flue for the products of combustion. It will be seen that the water in chamber E is subjected to intense heat and thereby rapidly converted into hot water and steam. As the inner wall of the upper section is corrugated, a great heating-surface is produced and increased strength added to said section. In order to produce a tight joint between the sections, packing or gasket α , of suitable material, is interposed between the same and clamped by the tightening of the bolts H, as will be seen in Fig. 3.

Having thus described my invention, what I claim as new, and desire to secure by Letters Patent, is—

1. A steam-generator having a sectional furnace with an outer space forming a water-leg, the inner wall of which is doubly inclined, the chamber E above said water-leg and furnace and containing the flues B B', the packing α between the sections of the water-leg, and the bolts H, binding the said sections together, said parts being combined substantially as described.

2. A steam-generator having a furnace with an outer space forming a water-leg, the inner wall of which is doubly inclined, the chamber E above said water-leg and furnace and containing the flues B B', the upper inclined wall being corrugated, said parts being combined substantially as described.

3. In a steam-generator, the combination of a furnace with an outer space forming a water-leg, the inner wall of which is doubly inclined, as described, and the upper inner wall is corrugated, the chamber E above said furnace and water-leg, and provided with the flues B B', the latter connected by the sheets C C, a passage being formed between the rim of the lower of the said sheets C and the corrugated surface of the inner wall of the water-leg, substantially as and for the purpose set forth.

4. In a steam-generator, a water-chamber having a central depending rim formed by a

lower tube-sheet, with flues connected with said rim, in combination with a water-leg which converges and acts as a deflector for the products of combustion for the top water-space, substantially as described.

25

5. A steam-generator having a depending rim and flues connected therewith, and a peripheral portion above the base of said rim, with flues connected therewith, in combination with a water-leg which encircles said rim and directs the products of combustion to the flues of the depending rim and is corrugated or spaced to direct the products of combustion to the flues of the peripheral rim, substantially as described.
